UNITED STATES PATENT OFFICE.

CLARENCE EDWARD ROE, OF WINNIPEG, AND JAMES COLLINSON, OF SOURIS, MANITOBA, CANADA.

CAR-DOOR CLOSURE.

No. 833,244.

Specification of Letters Patent.

Patented Oct. 16, 1906.

Application filed July 16, 1906. Serial No. 326,333.

To all whom it may concern:

Be it known that we, CLARENCE EDWARD ROE, of 641 Young street, city of Winnipeg, and JAMES COLLINSON, of the town of Souris, Province of Manitoba, Dominion of Canada, have invented certain new and useful Improvements in Car-Door Closures, of which the following is a full, clear, and exact description.

Our invention relates to improvements in car-door closing and locking devices; and its object is to provide simple and inexpensive means for closing and automatically locking car-doors.

A further object is to provide means whereby a car-door may be readily opened or closed by a person standing on the ground beside the car.

To accomplish these objects, we provide a bar of suitable dimensions forked at one end to engage the car-door and sliding at the opposite end in a guide fixed to the car. This bar is provided with a pin surrounded by a loose sleeve which engages a slot in the end of a pivoted lever. The opposite end of the lever is provided with a handle and is adapted to engage a spring locking-catch fixed to the car. The lever and the spring-catch are furnished with holes adapted to register with one another in order that the wire of a seal may be passed therethrough.

Referring to the drawings, Figure 1 is a side elevation of our device attached to a car-door and shows the position of the parts when the door is closed. Fig. 2 is a side elevation similar to Fig. 1, but shows the door open. Fig. 3 is a perspective view of the sliding bar. Fig. 4 is a plan view of the pin and sleeve and shows a portion of the bar. Fig. 5 is an enlarged side elevation of the spring locking-catch.

In the above-defined figures, 1 designates a freight-car having a door 2. A bar 3 is provided at one end with a pair of broad plates 3^a adapted to lie on each side of the door and be sunk flush with the surface thereof. Toward the center of the bar 3 is a pin 4, surrounded by a loose sleeve 14, which engages a slot 4^a in one end of the lever 6. The end of the bar 3 remote from the door 2 is supported by a guide 5. The lever 6 is provided toward its center with a slot 7^a, engaging a pin 7, mounted in a block 8,

which is fixed to the car 1. The pin 7 is provided with a sleeve similar to the sleeve 14. 55 The opposite end of the lever 6 is provided with a hole 11 and a handle 6^a. The lever 6 is also bent outwardly at 12 and again at 13, as shown in Fig. 3. In the path of that part of the lever 6 adjacent the handle 6^a is a block 9, carrying a spring-catch 10, approximately of the form shown in Fig. 5. The free end of this spring-catch is provided with a hole 11^a, adapted to register with the hole 11 in the lever, so that the wire of a seal may 65 be passed through the two holes when the door is in locked position, as shown in Fig. 1. The lever 6 is prevented from slipping out of engagement with the pins 4 and 7 by means of straps 15 or other suitable means. 70

The operation of the device, considering the door to be closed and locked, as in Fig. 1, and sealed, consists in removing the seal in the usual manner and then depressing the spring-catch 10 to free the lever 6. The operator then grasps the handle 6^a and throws it to the left until the door 2 is open as far as desired. The slots 4^a and 7^a will take up the curvilinear motion of the lever, and the sleeves 14 render the bearing of the lever on 80 the pins 4 and 7 almost frictionless. 75

The advantages of this device will be obvious. Car-doors may be opened and closed with great ease and will be securely locked by the operation of closing. A further advantage is that the seals may be readily examined by the inspector when standing on the ground. 85

The device may be applied to any of the existing types of freight-car doors without 90 alterations in the door. The closure may be applied with equal facility to elevator-doors of similar type.

Having thus described our invention so that the same may be readily understood by 95 those skilled in the art to which it appertains, what we claim, and desire to secure by Letters Patent, is—

1. A device of the class described comprising a door, a bar rigidly secured thereto, 100 a guide for said bar, a centrally-pivoted lever attached to said bar, and means for locking said lever in position.

2. The combination with a car-door of a sliding bar secured thereto, a guide for said 105 bar, a centrally-pivoted lever attached to

said bar by means of a pin operating in a slot in said lever, and means for locking said lever in position.

3. The combination with a car-door of a sliding bar rigidly secured thereto, a guide for said bar, a centrally-pivoted lever coöperating with said bar by means of a pin operating in a slot in said lever, and means for automatically locking said door in closed position.

4. The combination with a car-door of a sliding bar rigidly secured thereto, a guide for said bar, a centrally-pivoted lever provided with a longitudinal end slot, a pin in the sliding bar operating in said slot, whereby said lever is capable of arcuate motion, and means for automatically locking said door in closed position.

5. The combination with a car-door of a sliding bar secured thereto, a guide for said bar, a centrally-pivoted lever provided at its pivotal point with a longitudinal slot, a second slot in the end of said lever coöperating with a pin in said sliding bar, and means for automatically locking said door in closed position.

In witness whereof we have hereunto set our hands in the presence of witnesses.

CLARENCE EDWARD ROE.
JAMES COLLINSON.
